DAVID ALDRICH, OF NEW YORK, N. Y., ASSIGNOR TO PHELAN & COLLENDER,
OF NEW YORK CITY.

Letters Patent No. 77,436, dated May 5, 1868.

IMPROVEMENT IN CUE-TRIMMERS.

The Schedule referred to in these Letters Patent and making part of the same.

TO ALL WHOM IT MAY CONCERN:

Be it known that I, DAVID ALDRICH, of New York, of New York county, in the State of New York, have invented a certain new and useful "Improved Cue-Cutter;" and I do hereby declare that the following is a full and exact description thereof, reference being had to the accompanying drawings, making part of this application.

My invention relates to a new machine or instrument for cutting the ends of billiard-cues preparatory to putting the tips or "leathers" on them.

Previous to my invention, the machine or instrument in most general use in billiard-rooms for trimming the ends of cues has been composed of a tubular holder, provided with a cutter, secured on the end of a spring shank, and so arranged that by pressing upon the said shank, (after having inserted the cue in the holder,) and turning the cue, the cutter would remove a piece from the cue-end, and leave the latter in a proper condition to receive the leather or tip in the manner well known to those skilled in the art. But it has been found in practice that this kind of cue-trimmer, even when operated with by an expert, does not work successfully and satisfactorily, and that it very soon becomes so deranged and inoperative as to be almost wholly useless, and other devices or instruments have been devised, though none of them, to my knowledge, are fully successful.

To overcome the practical objections existing in cue-cutters as heretofore made, and to afford an instrument at once effective, simple, economic, and durable, and with which an experienced hand can perfectly trim the end of a cue ready to receive the leather, is the object of my invention, which consists in a cue-trimmer composed of a hollow hand-piece and cue-holder provided with a reciprocatory carriage at its upper end, carrying the cutter, and also in forcing along the said carriage and cutter by means of a lever or handle hung to the hollow hand-piece and cue-holder, all as will be presently fully described.

And my invention also further consists in making the cutter removable, and retaining it in the carriage or slide by means of the carriage-holder, all as will be presently more fully explained.

To enable those skilled in the art to make and use my invention, I will proceed to describe the construction and operation of one of my improved cue-trimming machines or instruments, referring by letters to the accompanying drawings, in which—

Figure 1 is a top view,

Figure 2 a longitudinal section,

Figure 3 a side view, and

Figure 4 detail views of the carriage and cutter.

In the several figures, the same part is designated by the same letter of reference.

A is a metallic hand-piece, which is made hollow, as illustrated, and which is formed at its upper end with a table, b, in which is arranged and works a cutter-carriage, C. This carriage is moved back and forth in suitable bearings, with a reciprocatory motion, by means of the upper end of a vibratory handle, D, moving in a mortise cut through said carriage, as clearly shown at figs. 1 and 2.

The handle D is pivoted at e to the hand-piece and cue-holder A, and is provided with a strong spring, f, to throw it always, when relieved, in such a position as to place the carriage ready for the introduction of the cue or stick. g is the cutter, which may be made of steel, and about in the shape shown, and this cutter, g, is inserted into the carriage b, and is retained in place by the tips 1, 2, of the bed or table on which said carriage rides.

At fig. 2 I have shown the cue or stick at m, and illustrated the machine as if in the operation of cutting the cue-end.

The operation of my improved cue-cutter will be readily comprehended by those familiar with the use of such tools. The cue being inserted within the hollow hand-piece A, as illustrated at fig. 2, and adjusted to the cutter g, so that the latter will bite at the point where it is desired to cut off the cue, the said cutter is forced

into the stick by pressing the handle or lever D toward the cue-holder A, while at the same time the cue *m* is turned round and round (in the usual manner) by the operator. And in this manner the end of the cue is trimmed or cut off in a perfect plane, and smoothly. It will be observed that the cutter *g*, being held laterally by the carriage C, and retained vertically within the table in which said carriage moves, will have a perfect reciprocatory motion, and will consequently cut the cue in a perfect plane, and smooth and evenly. The cutter *g* is so shaped and adapted to the carriage C, that when the latter is unshipped, the said cutter can be taken right out for sharpening, &c.

By having the carriage mortised through, and the end of the lever D passed through said hole, as shown and described; a very simple means of operating the said carriage is provided, and one which, very economically manufactured, is durable, and not liable to get out of order. Of course, the particular manner of holding the instrument to work it is not material, but I would suggest to have the instrument grasped in the right hand, with the lever D toward the palm, and the cue turned with the left hand.

It will be seen that while an instrument, such as shown and described, may be very cheaply manufactured, it will be exceedingly durable, and will work successfully in every particular.

I do not wish to be understood as limiting my claim of invention to any precise details of construction or proportion of parts; but, having fully described my improved machine or instrument for cutting or trimming cues,

What I claim therein as new, and desire to secure by Letters Patent, is—

1. The hollow hand-piece and cue-holder, with its table or slide-holder, *b*, in combination with a reciprocating carriage, provided with a cutter, substantially as and for the purposes set forth.
2. I claim the employment, in combination with the hollow cue-holder and hand-piece, of a reciprocatory cutter-carriage and the driving-lever D, the whole arranged to operate in the manner and for the purpose substantially as described.
3. I claim the removable cutter *g*, in combination with the cutter-carriage and table *b*, substantially as and for the purpose described.

In testimony whereof, I have hereunto set my hand and seal, this twenty-ninth day of February, 1868.

DAVID ALDRICH. [L. S.]
